UNITED STATES PATENT OFFICE.

EDMUND MERRIMAN WISE, OF CINCINNATI, OHIO, ASSIGNOR TO THE WADSWORTH WATCH CASE COMPANY, OF DAYTON, KENTUCKY, A CORPORATION OF KENTUCKY.

METHOD OF MAKING WATCHCASES.

Application filed July 27, 1923. Serial No. 654,109.

To all whom it may concern:

Be it known that I, EDMUND MERRIMAN WISE, a citizen of the U. S., residing at 1105 Elm Street, Cincinnati, in the county of 5 Hamilton, State of Ohio, have invented certain new and useful Improvements in Methods of Making Watchcases; and I do hereby declare the following to be a full, clear, and exact description of the invention, 10 such as will enable others skilled in the art to which it appertains to make and use the same.

This invention relates to methods of making watch cases, and, more particularly, to 15 a method of making solid gold watch cases by means of dies designed for the purpose of shaping watch case stock having a thickness considerably greater than that of the stock out of which the solid gold watch cases 20 are made. In other words, this invention relates particularly to a process whereby a watch case can be made out of thin stock by using dies designed for the purpose of handling relatively thick stock.

25 The general practice in making solid gold watch case backs consists in casting an ingot of a suitable gold alloy, and rolling the ingot down, with suitable intermediate annealing, to substantially the thickness required for 30 the watch case. For example, the stock may be rolled to its ultimate thickness plus .0005 of an inch and then cut up into blanks which are stamped with a serial number and trade mark, and then rolled about .0005 of an inch 35 to flatten them. The blanks are then put into a punch press which stamps them out to a shape suitable for the watch case back. Each of the blanks is then drawn into a shallow cup, and the upright edges are folded 40 towards the center until the blank assumes a form approximating its final shape. The back is then finished by the usual rolling and turning operations, and the joints, if any, are soldered on. The back is polished 45 and it is then complete.

The bezel and center are made in substantially the same manner in which the watch case back is made, although in making the center the press is relied upon only to form 50 the metal very roughly into the required shape, the final forming being done by spinning. Subsequent to the spinning operation the center is turned on the inside to lighten it, the joints, lugs, etc. are soldered in place 55 and then the center is polished.

It is oftentimes desirable to make a series of watch cases, each having substantially the same external dimensions, but the several cases of the series being made of gold stock of different thicknesses. If this were to be 60 done in the ordinary manner, a different set of dies would be required for each thickness. Heretofore it has not been considered possible to use a set of dies designed to be used with watch case stock of a given thickness, 65 for shaping stock substantially thinner than that for which the dies were designed. Accordingly, the principal object of the present invention is to provide a process of making watch cases whereby a single set of dies may 70 be used for making cases out of stock of different thicknesses. In general, this object is accomplished by increasing the effective thickness of the thin stock merely for the purpose of putting it through the dies. This 75 can be done by applying to the stock a layer of base metal so as to increase the effective thickness of the stock the desired amount. After the stock has been shaped by means of the dies, this layer of base metal is removed. 80

The various details of the preferred embodiment of this invention will now be described with reference to the accompanying drawings, in which

Fig. 1 is a plan view of a blank consisting 85 of solid gold stock to which a layer of base metal has been applied for the purpose of increasing the effective thickness of the stock.

Fig. 2 is an elevation of the blank illustrated in Fig. 1, showing the two layers of metal.

Fig. 3 is a transverse section view of a watch case back formed from the composite blank illustrated in Figs. 1 and 2. 95

Fig. 4 is a plan view of the watch case back shown in Fig. 3, part of the layer of base metal having been removed.

Fig. 5 is a transverse sectional view of the watch case back shown in Fig. 4, and 100

Fig. 6 is a transverse sectional view of a watch case back formed from a composite blank, the layer of base metal being on the inside of the watch case back.

In carrying out the preferred embodiment 105 of my invention, I apply to the watch case stock a layer of base metal such as copper, the thickness of the layer of base metal being sufficient to increase the effective thickness of the stock so that it can be handled 110

properly by the dies. The watch case stock may be an alloy of gold or silver, or in fact any metal out of which solid watch cases are made, the term "solid" being used to distinguish cases such as solid gold cases from gold filled cases. It is therefore to be understood that the term "solid gold" as used throughout this description and the appended claims includes all metals which are used for the purpose of making watch cases. The solid gold stock should be rolled to substantially its ultimate thickness before the layer of base metal is applied thereto, for if the metal has to be rolled considerably after the base metal is applied thereto, objectionable irregularities are apt to be formed on the surface of the gold.

The layer of base metal may be applied to the solid gold in any suitable manner, the only limitation being that the layer of base metal must not be applied so as to appreciably impair the surface of the watch case stock. Heretofore, certain watch case parts have been made out of composite stock formed by sweating or soldering a layer of base metal to a layer of gold and rolling the composite bar down to the desired thickness, after which the usual mechanical operations are performed and the base metal removed. This process is not suitable for the making of solid gold watch case backs, or for any other purpose which requires the surface of the underlying precious metal to be preserved in its original form. The surface of the gold where it has been in contact with the base metal is rough, this probably being due to the slight penetration of the solder used to form a composite bar, and partly due to the deformation taking place during the rolling operations necessary to reduce the stock to its ultimate thickness.

One of the important features of the present invention consists in applying the layer of base metal only after the gold stock has been rolled to substantially its ultimate dimensions. This feature effectively removes the danger of impairing the surface of the gold stock by rolling it after the base metal has been applied thereto. Furthermore, the base metal should not be applied to the gold stock in such a manner that it will alloy with or penetrate the gold to any appreciable extent. I have found that very satisfactory results can be obtained by electroplating the layer of base metal on to the gold stock. By this means the effective thickness of the stock can be increased to the exact value desired, and when the base metal is removed the underlying surface of the gold is preserved in its original condition. While I prefer to electroplate the base metal on to the gold stock, yet the base metal may be welded thereto, if proper precautions are taken to preserve the adjacent surface of the gold stock. In any

event, the gold stock should be rolled to substantially its ultimate thickness before the layer of base metal is applied thereto.

The watch case blank shown in Figs. 1 and 2 has been stamped from composite stock consisting of a layer 1 of solid gold or other watch case metal, and a layer 2 of base metal which has been applied to the gold stock, preferably by electroplating. The underlying gold stock may have a thickness of, for example, .012 of an inch, and if this stock is to be put through dies designed for stock having a thickness of .022 of an inch, the layer 2 of base metal should have a thickness of .010 of an inch.

Fig. 3 shows the blank of Figs. 1 and 2 drawn into a shallow cup, the configuration of which is substantially the same as that of the finished watch case back. This cup is subjected to the usual turning operations, and then the layer of base metal is removed by means of a suitable acid.

Figs. 4 and 5 show a watch case back with a part of the layer 2 of base metal removed, revealing the layer 1 of solid gold. I have found that by applying the layer of base metal after the gold stock has been rolled to its ultimate thickness, and applying it so that it does not impair the surface of the gold, the solid gold may be ornamented or marked in any desired manner before the base metal is applied thereto, with the assurance that the ornamentation will not be injured in any way by the base metal. In the drawing I have illustrated a watch case having initials 3 engraved thereon. These initials were applied to the gold stock before the layer of base metal was deposited thereon.

Fig. 6 shows a watch case back similar to that shown in Fig. 3 except that the layer 2 of base metal is deposited on the inside of the layer 1 of solid gold instead of on the outside. It is immaterial whether the composite stock be shaped so that the layer of base metal is on the inside or on the outside. For some purposes it may be preferable to have the layer of base metal on the inside. In either case, this layer of base metal is removed after the case is completely formed.

This invention is not limited to the particular embodiments illustrated and described, but includes such modifications thereof as fall within the scope of the appended claims.

I claim:

1. The process of making solid gold watch cases, which consists in providing solid gold stock rolled to substantially its ultimate thickness, applying to the gold stock a layer of base metal in such a manner that the adjacent surface of the gold stock is not appreciably affected by the application of the layer of base metal, shaping the composite

metal into a watch case without first reducing the thickness of the composite metal, and removing the layer of base metal.

2. The method of making solid gold watch cases which consists in providing solid gold stock rolled to substantially its ultimate thickness, ornamenting the gold stock, applying to the ornamented surface a layer of base metal to increase the effective thickness of the stock to a predetermined value, shaping the composite stock by means of dies adapted to shape metal having a thickness equal to the predetermined value, and subsequently removing the layer of base metal.
- 15 3. The method of making solid gold watch cases, which consists in providing solid gold stock rolled to substantially its ultimate thickness, electroplating a layer of base metal on to the gold stock to increase

its effective thickness to a predetermined value, shaping the composite stock by means of dies adapted to shape metal having a thickness equal to the predetermined value, and subsequently removing the layer of base metal.

20 4. The method of making a solid gold watch case by means of dies adapted to shape metal having a thickness substantially greater than that of the solid gold stock out of which the case is to be made, which 25 consists in increasing the effective thickness of the solid gold stock by electroplating thereon a layer of copper, shaping the composite stock by means of the dies, and subsequently removing the layer of base metal.

30 35 In testimony whereof I affix my signature.

EDMUND MERRIMAN WISE.
